SAFETY HELMET

Brock F. Brockway, Mill Valley, Calif., assignor to E. D. Bullard Company, Sausalito, Calif., a corporation of California

Filed Dec. 4, 1964, Ser. No. 82,908

Term of patent 14 years

(Cl. D3—13)

FIG. 1 is a perspective view of a safety helmet showing my design;

FIG. 2 is a side elevational view, the side opposite being a mirror image thereof;

FIG. 3 is a front view;

FIG. 4 is a rear view;

FIG. 5 is a top view; and

FIG. 6 is a bottom view.

I claim:

The ornamental design for a safety helmet, as shown.
